SAFETY DEVICE FOR AMUSEMENT
PARK RIDES

William B. Schmidt, Chicago, Ill.

Application December 1, 1944, Serial No. 566,139

9 Claims. (Cl. 188—111)

1

This invention relates to amusement park rides and has for its principal object the provision of safety devices therefor.

It is a main object of the invention to provide an automatic brake setting mechanism that operates to set the brake automatically in the event that the brake is not manually set before an approaching train reaches a predetermined point.

A further object of the invention is to provide a means for rendering the automatic brake setting mechanism inoperative when the brake is set in the usual manner thereby to render the automatic mechanism useable only in cases of emergency.

Still another object of the invention is to provide an automatic brake setting mechanism that can be installed in existing rides and in conjunction with existing brakes and brake setting mechanisms.

Still another object of the invention is to provide an automatic brake setting mechanism that can be manufactured as a rugged unit at low cost and can be economically installed and maintained in a ride.

Further objects of the invention not specifically mentioned here will be apparent from the detailed description and claims which follow, reference being had to the accompanying drawings in which a preferred embodiment of the invention is shown by way of example and in which:

Figure 1 is a diagrammatic view of a ride showing the apparatus of the present invention there-in installed;

Figure 2 is a diagrammatic view illustrating the automatic brake setting mechanism of the present invention;

Figure 3 is a fragmentary cross sectional view taken substantially along the line 3—3 of Figure 1 and drawn to an enlarged scale; and

Figure 4 is a fragmentary cross sectional view taken substantially along the line 4—4 of Figure 3.

Amusement park rides frequently have free running trains, sometimes consisting of a single car and sometimes a plurality of cars coupled together as a train. The movement of such devices is usually controlled by stationary brakes located in the path of the cars and engaged thereby to bring the train to rest at a desired point. The present invention is applicable to all such rides, but herein it is shown applied to so-called roller coasters which serve as an excellent example of an application of the invention.

Roller coasters usually comprise a trackway having a high point to which trains are hauled,

2

generally by a chain mechanism, and the train released to travel over the remainder of the trackway under the force of gravity. The trackway contains hills, valleys and sharp curves, as desired, to add thrills to the ride. At the end of the ride the trackway leads into an unloading platform at which the train is stopped by a suitable brake mechanism to permit passengers who have completed the ride to disembark. The trackway is downhill so that when the brake at the unloading platform is released the empty train will move forwardly to the loading platform where it is brought to rest by a similar brake mechanism. When the train is loaded the brake at the loading platform is released and the train rolls downhill to the bottom of the chain, where it is picked up and propelled to the high point of the ride.

The brakes at both the unloading and loading platforms are manipulated by manual levers that are operated by attendants on the respective platforms. Most generally these levers are connected to the brake setting mechanism by suitable rods and bell cranks so that the force put on the hand lever by the attendant is the force that sets the brake. However, in certain instances electromagnetic or pneumatic means are employed to set the brakes and the hand lever serves merely as a control for such mechanisms.

30 A loaded train approaching the unloading platform usually travels at a speed of approximately thirty miles per hour, and it is necessary that the attendant have the brake at the unloading platform set prior to the entrance of the train into the braking zone. Should he fail to set this brake in time or, in the case of a power driven brake, should the power fail, the rapidly moving train will run through the unloading platform and may crash into a preceding train which is at 35 the loading platform—or, if there be no train at the loading platform, continue on at an excessive speed to the bottom of the ride where, because of excessive speed, damage to the train and trackway and injury to the passengers may result.

40 45 The present invention provides a safety device through the operation of which the brake at the unloading platform is automatically set by the train itself as that train enters the approach to the unloading platform, if the attendant has not previously set the brake in the usual manner. The train operated automatic brake setting mechanism is rendered inoperative each time the brake is operated in the usual manner.

In the preferred embodiment of the invention a trigger is located in the trackway in the ap-

proach to the unloading platform and at a distance from the brake sufficiently great to insure that the automatic brake setting mechanism will operate to fully set the brake after the train has run over the trigger and before the train has reached the brake. It has been found that placing the trigger one hundred fifty feet from the brake is satisfactory in most instances, although a greater or lesser distance may be employed within the teachings of the invention.

Train operated triggers of various kinds have been used heretofore in the prior art, of which I am aware. However, in instances where these triggers have been rendered inoperative by a manual operation of a brake lever, the weight and friction of the trigger displacing mechanism has added such a drag on the manual brake setting mechanism as to render hand setting of the brake difficult if not impossible. The present invention in its preferred form provides a new and improved trigger and trigger displacing mechanism which is free running and adds no appreciable drag to the manual brake setting lever.

Referring now to the drawings in more detail—the trackway 1, Figure 1, is shown as a simple oval, by way of example, but it will be understood that this trackway may abound in hills, valleys and curves within the teachings of the invention. A chain 2, driven by a motor 3, operates to elevate train to the high point 4 of the trackway, the train passing off of the upper end of the chain and over the trackway under the force of gravity. The unloading platform 5 is equipped with a brake 6 that is operated by manual lever 7 moving from the solid line to the dotted line position to set the brake to stop a train. Adjacent the unloading platform 5 is the loading platform 8 which is equipped with a brake 9 that is controlled by a lever 10 to stop train at this platform. Located on the trackway in the approach to the brake 6 is a trigger mechanism 11 thru the operation of which automatic setting of the brake is accomplished.

As will be seen in Figure 2 the brake 6 consists of main members 15 which extend longitudinally of the trackway 2 between the rails. The members 15—usually two in number—are adapted to be elevated into their set position by suitable means, such as toggles 16 and 17, which are operated through the movement of an operating rod 18 by an actuator. In the case of a manually actuated brake the actuator 19 will consist of suitable bell cranks and rods connecting the lever 17 to the rod 18 in such manner that movement of the lever 7 from the solid to the dotted line position in Figure 1 will move the rod 18 to the right, Figure 2, to elevate the brake members 15. The particular type of brake mechanism is not of the essence of the present invention and the toggle operated vertically movable brake is shown by way of example only.

Located on the trackway and resting on the supporting ties 20 thereof, is a mounting block 21 which carries the trigger 22. Also, mounted on the trackway and between adjacent ones of the ties 20, are sheaves or pulleys 23 around which is threaded a cable 24, the opposite ends of which cable are secured to the opposite ends of the mounting block 21. Cable 24 is also connected to rod 18 by suitable clamp means 25. In the drawings the trigger is located on a straight portion of the track leading to the unloading platform and two sheaves 23 are all that are shown. In many instances the track will contain a curve that is so close to the unloading platform that it will be

necessary to locate the trigger beyond the curve. In such a case such additional sheaves as may be required will be used to position and support the cable. Also it may be necessary to support cable 31 in suitable sheaves, which have been omitted from the drawings to avoid an unnecessary complication thereof.

The automatic brake setting mechanism shown by way of example consists of a fixed pulley 26 around which a cable 27 is extended. One end of the cable 27 is fixed to the rod 18 and the other end to an actuator which is shown to comprise a pivoted lever 28 that is held in substantially horizontal position by a latch 29 that is pivoted at 30. The latch is held in normal position by a spring 33. A weight 34 is suspended from lever 28. Trigger 22 is connected to the latch 29 by suitable means such as cable 31.

With the brake members 15 in their lower or normal position, the toggles 16 and 17 will be sprung as shown in Figure 2, and rod 18 will be at the left end of its path of movement. Mounting block 21 will be in such position that the trigger 22 extending upwardly therefrom will lie in the path of a brake shoe 32 on the train and as the train moves to the right trigger 22 will be rotated clockwise around its pivot, thereby moving cable 31 to the left to withdraw the latch from beneath the lever 28, permitting that lever to descend and through cable 27 pull rod 18 to the right, thereby straightening out the links of the toggles 16 and 17 and elevating the brake members 15 into the path of the brake shoe 32, so that when the train reaches the brake it will be stopped. Movement of the trigger around its pivot tensions spring 33. Movement of the rod 18 to the right moves the pivot of the trigger 22 to the right, thereby moving the trigger out of the path of the shoe in a manner which will be presently described. This releases the tension on cable 31 to permit spring 33 to restore the trigger into position to hold the weight elevated when next it is elevated.

As soon as the train on brake 6 is ready to proceed off of the brake, lever 7 is moved from the dotted to the solid line position, Figure 1, thereby moving rod 18 to the left, Figure 2, to lower members 15 through the action of toggles 16 and 17. This movement may elevate weight 34 into the position shown in Figure 2. Since the weight 34 is quite heavy a substantial amount of power will be required on the lever 7 to elevate the weight by this means, and it may be necessary for the attendant at the unloading platform to call upon the attendant at the loading platform to assist him in re-setting automatic brake mechanism to its normal position. This is desirable, since this automatic mechanism moves out of normal only when the attendant is careless and frequent requests for help will not meet with the approval of the loading platform attendant. In certain instances it may be advisable to make the weight 34 so heavy that it cannot be re-elevated by a manipulation of the lever 7, but rather a suitable winch or block and tackle (not shown) will have to be used to re-set the weight.

Toggle links 16 and 17 are moved past the point where the three pivots are in alignment as the brake is set thereby to lock the toggle in the usual manner. Stop block 35 is engaged by lever 28 at the instant that the pivots are in alignment or slightly before they are in alignment and the movement of the links and rod 18 past this dead center position places a small amount of slack in cable 27. This arrangement enables the attendant to operate lever 7 suffi-

ciently to release the brake when a train is standing thereon even in cases where the weight 34 is too heavy to be re-set by an operation of the lever. The slack in cable 27 enables the attendant to move the toggle links into the dead center position and the weight of the train on the brake aids in releasing it at least enough to permit moving the train off the brake.

As will be seen in Figures 3 and 4 in its preferred form the trigger mechanism consists of a plate 40 mounted upon the trackway ties 20, and carrying generally L-shaped guides 41 which fit over the bottom flanges 42 of angle irons whose upper flanges 43 are spaced apart by suitable blocks 44, and are substantially parallel to each other. Located between the flanges 43 and extending through a suitable opening 45 in the plate 40 is the trigger 22 hereinbefore referred to. The trigger may be provided with suitable bosses 46, which place it centrally in the space between flanges 43 and which are pierced to receive a bolt or rod 47 that pivotally supports the trigger on the mounting block 21. It will be noted that member 22 herein referred to as a trigger is shaped so that when it is engaged by the brake shoe 32, the trigger is moved by a camming action of the trigger and shoe. That is the trigger is rotated gradually rather than being tripped or knocked out of the way by the shoe. This gradual movement lessens the shock to the trigger and apparatus connected thereto, thereby prolonging its life.

Plate 40 is located between the rails 59 of the trackway, these rails consisting of the usual plate 51 for receiving the load supporting wheel 52, side thrust plate 53 against which the side thrust wheel 54 of the car engages and the up-thrust plate 55 against which the up-thrust wheel 56 of the car engages. The particular type of rail and the particular wheel arrangement of the car is not of the essence of the present invention.

Plate 40 is located to one side of the center of the trackway so that trigger 22 will be in line with the center of the brake shoe 32 carried beneath the car.

Mounted beneath the ties 20 is a stop block 48 against which the bottom portion of the trigger 22 normally rests. The point of engagement of the cable 31 to the trigger is located as near to the lowermost point of stop block 48 as possible.

Cable 24 is connected to opposite ends of the block 21 by suitable means such as U-clamps 49. When rod 18 moves to the right to set the brake members 15 in their uppermost position, the mounting block 21 will slide on the plate 40 to the right, Figure 4. This movement moves the pivot bolt 47 by which the trigger is mounted on the block to the right into the position in which it is shown in dotted lines in Figure 4. During this movement of the mounting block to the right, trigger 22 moves around the apex of the stop block 48 as a fulcrum and the upper end of the trigger moves out of the path of the brake shoe 32. Since the point of attachment of the cable 31 to the trigger 22 is near the fulcrum point of the trigger during this movement, cable 31 is not moved sufficiently to unlatch the weight 34, and that weight therefore remains in its uppermost position. Movement of rod 18 to the right, Figure 2, puts slack in the cable 27 without effect at the time.

When the lever 1 is operated to release the brake, thereby to permit the train to move away from the loading platform, mounting block 21 is moved to the left, Figure 4, and trigger 22 is

moved back into the path of brake shoe 32 so that should another train arrive at the trigger before the brake 6 is reset to stop it, the train will set the brake in the hereinbefore described manner.

The present invention is possessed of many advantages. It may be installed in a vast majority of the existing rides in a simple and relatively inexpensive manner and when installed it does not add sufficient drag on the manually operated brake setting mechanism to be noticeable. When properly adjusted, the mechanism will set the brake when that brake has been left in its normal position, and when the brake has been moved but partially into its set position. The use of the mechanism of the present invention eliminates the possibility of a train running through the unloading platform because the attendant has forgotten to set the brake, or has but partially set it or—in the case of a power operated brake—because of a power failure. The devices required to put the present invention into use are not expensive to construct and install, and maintenance of the device is very low.

While I have chosen to illustrate my invention, by showing and describing a preferred embodiment of it, I have done so by way of example only, as there are many modifications and adaptations which can be made by one schooled in the art within the teachings of the invention.

Having thus complied with the statutes and shown and described a preferred embodiment of my invention, what I consider new and desire to have protected by Letters Patent is pointed out in the appended claims.

What is claimed is:

1. In a safety device for an amusement park train, a brake, means for setting said brake to stop a train, a trigger adapted to be operated by a train to set said brake and stop said train, and means actuated by said brake setting means for moving said trigger out of the path of a train.

2. In a safety device for an amusement park train, a brake, manually controlled means for setting said brake to stop a train, a trigger adapted to be actuated by a train, automatic means controlled by said trigger for setting said brake to stop the train, and means actuated by said manually controlled brake setting means moving to set the brake to stop a train for moving said trigger out of the path of a train.

3. In a safety device for an amusement park ride, a trackway over which trains run, a brake on said trackway, manual means for operating said brake to set it to stop a train, a trigger located on the trackway in the approach to said brake, and automatic means controlled by said trigger when the trigger is operated by being struck by the train to set said brake independently of said manual means.

4. In a safety device for an amusement park ride, a trackway over which trains run, a brake on said trackway, means for operating said brake to set it to stop a train, a weight, means for holding said weight in an elevated position, means connecting said weight to said brake operating means, a trigger located on said trackway, and means actuated by a train hitting said trigger for operating said means for holding said weight to cause the weight to fall and thereby set said brake to stop said train.

5. In a safety device for an amusement park ride, a brake, means for actuating said brake to stop a train, a mounting block, a trigger pivotally mounted on said block, and means actuated

by said brake actuating means for moving said mounting block and trigger thereby to move the trigger out of the path of the train.

6. In a safety device for an amusement park ride, a trackway, a brake on said trackway, an actuator operable to set the brake to stop the train, a weight, means connecting said weight to said brake, latch means for holding said weight in an elevated position, a trigger located on said trackway in position to be struck by a train thereon as said train approaches said brake, and means connecting said trigger to said latch means and operable when the trigger is struck by the train to permit said weight to fall and thereby operate said brake to stop the train.

7. In an amusement park ride, a trackway, a train adapted to run over the trackway, an unloading platform, a brake on the trackway movable from a normal into a set position in which set position the brake will stop the train at the unloading platform, manually controlled means for moving said brake from normal to set position, automatic means for moving said brake from normal to set position independently of said manually controlled means, a trigger located on said trackway in the approach to said unloading platform and having a normal and a set position, means connecting said trigger to said brake and operable to move the trigger from normal to set position simultaneously with a movement of the brake from normal to set position, means on said train adapted to strike and operate the trigger only when the trigger is in said normal position and means responsive to an operation of the trigger for operating said automatic means to move said brake from normal to set position to stop said train at the unloading platform.

8. In a safety device for an amusement park ride, a trackway, a brake on said trackway, means including a longitudinally movable rod for setting said brake to stop a train, a mounting block, means securing said block on said trackway for limited longitudinal movement therealong, a trigger pivotally mounted on said block and extending into the path of a train on said trackway, means controlled by said trigger rotating on

its pivot mounting when struck by a train for setting said brake to stop the train, a stop block fixed below the trackway and engaged by said trigger, manually controlled means for moving said longitudinally movable rod to set said brake to stop a train, and means connecting said mounting block to said rod to cause movement of the rod to move said mounting block longitudinally along the trackway and thereby rotate said trigger around said stop block as a fulcrum to move the trigger out of the path of a train.

9. In an amusement park ride, a trackway, a train adapted to run over the trackway, an unloading platform, a brake on the trackway movable from a normal into a set position in which set position the brake will stop the train at the unloading platform, means including a longitudinally movable rod for moving said brake from normal to set position, manually operable means for actuating said brake setting means, a mounting block slidably mounted on said trackway in the approach to said unloading platform, cable means connected to said mounting block and movable rod and adapted on movement of the rod to move the brake from normal to set position to move the mounting block from normal to set position, automatic means for moving said brake from normal to set position independently of said manually operable means, a trigger pivoted on said mounting block and disposed in the path of the train when the block is in normal position, and means actuated by the striking of said trigger by the train for operating said automatic means to set the brake to stop the train.
